UNITED STATES PATENT OFFICE

2,266,109

METALLIC BED CONSTRUCTION

Louis J. Wiener, New York, N. Y.

Application March 30, 1938, Serial No. 198,839

4 Claims. (Cl. 5—280)

My invention relates to metallic bed constructions. More particularly, my invention relates to a novel construction for foot and head pieces of metallic beds.

One of the objects of my invention is to provide a novel and improved construction for foot and head pieces for metallic beds so designed as to present the appearance of a wooden bed.

Another object of my invention is to provide a novel and improved construction for foot and head pieces for metallic beds in which the panel members are attached to the frame members in such manner whereby no seams or ridges of junction will be visible when the bed is viewed from the front.

Still another object of my invention is to provide a novel and improved construction for foot and head pieces for metallic beds which shall comprise relatively few and simple parts, which shall be easy to assemble, rugged in construction and which, at the same time, shall be highly efficient for the purposes intended.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing, in which is shown one of the various possible embodiments of this invention,

Fig. 1 is a perspective view of a head piece for a metallic bed constructed in accordance with my invention.

Fig. 2 is an enlarged perspective view of the rear of a portion of the head piece shown in Fig. 1, being cut vertically to disclose the construction thereof.

Fig. 3 is an enlarged cross-sectional view taken substantially on the line 3—3 of Fig. 2.

Fig. 4 is a plan view of the stamping which forms the panel part of the head piece illustrated in Fig. 1.

Fig. 5 is a perspective view similar to Fig. 1 but illustrating a foot piece constructed in accordance with my invention; and

Fig. 6 is an enlarged cross-sectional view taken substantially on the line 6—6 of Fig. 2.

Referring now in detail to the drawing, there is disclosed a head piece 10 and a foot piece 11 of a metal bed constructed in accordance with my invention. These head and foot pieces 10 and 11

are preferably of similar design and construction and may be made of equal size or, if desired, they may vary in height, as shown. Each of said head and foot pieces may comprise a metallic frame member having a pair of parallel vertically disposed legs 12 interconnected adjacent their upper ends by a transverse portion 14. The portion 14 may be permanently attached to the legs 12 by any suitable attaching means well known in the art, such as welding or soldering, to form a unitary frame member which may be in the form of an inverted U, as shown, or which may be of any other desired shape. The legs 12 and the transverse portion 14 may be of hollow construction in order to minimize the weight and may be of any desirable cross-sectional contour shown in the drawing. Attached to the metallic frame just described is a metallic sheet member 15 which is so designed that when it is attached to the metallic frame all of the transverse portion 14 and all, or substantially all, of the legs 12 will be concealed when viewed from the front, thus presenting a neat, smooth and even surface without visible seams to mar the smooth effect.

In Fig. 4 of the drawing I have shown in reduced scale a stamping or blank of the member 15, which comprises a flat sheet of suitable metallic material having a rectangular portion a, b, c, d and lateral extensions e, f, g, c, and e, f, a, g, disposed on opposite sides thereof. Extending laterally from the said extensions, are portions h, k, m, and g. Extending from the bottom edge of the portion a, b, c, d is a portion p, r, s, t.

In attaching the member 15 to the tubular frame the extensions h, e, f, c, g, k and h, e, f, a, g, k, are folded on the lines f, c, and f, a, to lie at right angles to the rectangular portion a, b, c, d, after which the last named rectangular portion may be caused to contactively overlie the corresponding flat sides 12a of the legs 12 and the member 14 in such manner whereby the extensions h, e, f, c, g, k, and h, e, f, a, g, k, will at the same time contactively overlie the corresponding outer flat sides 12b of the legs 12. It is noted that the upper part of the portion a, b, c, d extends above the transverse member 14 and that a portion of such upwardly extending portion is arched to conform to the curvature of the edges e, f and then folded over at A to lie parallel to and spaced from the portion a, b, c, d, as clearly shown in Fig. 2 of the drawing. A portion adjacent the extreme edge a, b of the member 15 is folded over on the fold line x, y to form the portion B contactively overlying the top surface

of the transverse member 14. The portions of the edges x, f and y, f , which are caused to be arched and to lie adjacent the extension edges e, f , may be joined in any suitable manner well known in the art, such as, for example, by soldering or welding.

To more firmly attach the metallic member 15 to the metallic frame above described, the lateral extension portions h, m, k, g are folded over the fold lines m, g to lie between the inner surfaces of the extensions e, f, g, c and e, f, a, g (which have now become the ends W of the head and foot pieces) and the faces 12b of the legs 12, as clearly shown in Fig. 6. The folded over portions h, m, k, g may then be weldedly attached to the legs 12 at spaced points D along said legs. In order to artistically finish off the bottom horizontal edge of the member 15 the portion p, r, t, s may be angularly folded over on the line p, r and again folded inwardly on the fold line u, v to assume the position as shown in Fig. 2 of the drawing.

It will thus be seen that there is provided a device in which the several objects of this invention are achieved, and which is well adapted to meet the conditions of practical use.

As various possible embodiments might be made of the above invention, and as various changes might be made in the embodiments above set forth, it is understood that all matter herein set forth or shown in the accompanying drawing is to be interpreted as illustrative and not in a limiting sense.

Having thus described my invention, I claim as new and desire to secure by Letters Patent:

1. A construction for foot and head pieces for metallic beds, comprising a frame member, and a panel member, said frame member having a pair of substantially vertically disposed leg portions and a transverse interconnecting member, said panel member comprising a rectangular portion and integral portions extending at a right angle from the plane of said rectangular portion and disposed on opposite sides of said rectangular portion, the upper edges of said extending portions being curved, said extending portions contactively engaging portions of the surface of said frame member, a portion of said rectangular portion adjacent the upper end thereof being arched to conform to the curvature of said upper edges of said extending portions and having portions of the opposite edges of said rectangular portion lying adjacent to said curved upper edges, said adjacently disposed curved edges being permanently joined.

2. A construction for foot and head pieces for metallic beds, comprising an inverted U-shaped frame member, and a panel member, said panel member comprising a rectangular portion and integral portions extending at a right angle from the plane of said rectangular portion and disposed on opposite sides of said rectangular por-

tion, said last named extending portions contactively engaging portions of the surface of said frame member, the upper part of said rectangular portion being folded over to lie parallel to and spaced from the unfolded part of said rectangular portion, said folded over portion projecting above said frame member and means permanently attaching said panel to said frame member, said panel member being so designed that when it is permanently attached to the frame member, all of the said frame member with the exception of a relatively small portion adjacent the bottom ends thereof will be hidden when viewed from the front to thereby simulate the type of foot and head pieces generally employed for wooden beds.

3. A construction for foot and head pieces for metallic beds, comprising a frame member, and a panel member, said panel member comprising a rectangular portion and integral portions extending at a right angle from the plane of said rectangular portion and disposed on opposite sides of said rectangular portion, said last named extending portions contactively engaging portions of the surface of said frame member, the upper part of said rectangular portion being curved and then folded over to lie parallel to and spaced from the unfolded part of said rectangular portion, and means permanently attaching said panel to said frame member, said panel member being so designed that when it is permanently attached to the frame member, all of the said frame member with the exception of a relatively small portion adjacent the bottom ends thereof will be hidden when viewed from the front to thereby simulate the type of foot and head pieces generally employed for wooden beds.

4. A construction for foot and head pieces for metallic beds, comprising a frame member, and a panel member, said frame member comprising a pair of substantially vertically disposed leg portions having front and side surfaces and a transverse interconnecting member, said panel member comprising a rectangular portion overlying said front surfaces of said frame member and integral portions extending at a right angle from the plane of said rectangular portion and disposed on opposite sides of said rectangular portion, a portion adjacent the outer edges of each of said extending portions being folded over into juxtaposition with said extending portions, said folded portions contactively engaging portions of the side surfaces of said frame member, said panel member being permanently attached to said frame member by welding the outer edge of each of said folded portions to the adjacent surface of said panel member, the upper part of said rectangular panel portion comprising a folded over portion projecting above and resting upon said transverse frame member.

LOUIS J. WIENER.
